COWL FOR CHIMNEYS OR VENTILATOR
SHAFTS

Thomas Augusto Leardi, London, Edmund John Long, County Durham, and Maurice Jack Stephens, Catford, London, England

Application August 2, 1946, Serial No. 688,080
In Great Britain July 5, 1945Section 1, Public Law 690, August 8, 1946
Patent expires July 5, 1965

4 Claims. (Cl. 98—78)

1

This invention relates to cowls for flues, chimneys or ventilator shafts and has for an object to provide an improved cowl by which the possibility of down-draughts occurring in the flue, chimney or ventilator shaft is substantially eliminated.

According to the present invention a cowl for a flue, chimney or ventilator shaft comprises a pipe member for mounting the cowl at the end of the flue, chimney or ventilator shaft, said pipe member having a nozzle-like outlet end portion, a plurality of hollow, open-ended, frusto-conical shields carried on the end of the pipe member above said end portion in vertically superposed relationship, each shield having its narrower end uppermost, each shield except the uppermost shield having its narrower end projecting into and inwardly spaced from the wider end of the shield next above, and the said outlet end portion of the pipe member projecting into and being inwardly spaced from the wider end of the lowermost shield, a plurality of open-ended vent pipes secured externally on the uppermost shield in circumferentially-spaced relationship, each vent pipe extending downwardly and outwardly from the uppermost shield and communicating at its upper end through a vent hole into the interior of the uppermost shield at a level spaced above the narrower end of the shield next below the uppermost shield, and a conical baffle member supported to be wholly within the uppermost shield and above the shield next below and having its apex downwards and its part of maximum diameter level with said vent holes.

Preferably two frusto-conical shields are provided.

One construction of cowl of this invention will now be described by way of example, the description having reference to the accompanying drawing which—

The figure is a perspective view of one construction of this invention partly broken away to show the internal details.

Referring to the drawing, a cowl suitable for preventing down-draught in a chimney flue or ventilator shaft, comprises a length of pipe 10 by which the cowl is mounted at the end of the flue or shaft. The pipe 10 is illustrated as being circular but the lower end thereof may be of any convenient cross section.

The upper end of the pipe 10 has a nozzle-like outlet 11 provided by a tapered portion 12 and carries in superposed relation thereon a plurality of hollow-open-ended frusto-conical shields, illustrated as two shields whereof the

2

lower shield is indicated by reference numeral 13a and the upper shield by reference numeral 13b, which shields are provided around their lower edges with integral lugs 14 by which the shields are secured to the pipe 10 or the shield next below it. The number of shields 13 may be varied, but preferably two such shields are provided. The shields 13 are arranged so as to be partially nested, that is with their narrower ends located within but in spaced circumferential relation to the wider end of the shield next above. Likewise the tapered end 12 of the pipe 10 is located within and in spaced circumferential relation to the wider end of the lowermost shield 13a.

The upper shield 13b is shown as being of greater length than the lower shield 13a but having substantially the same upper and lower diameters. At the upper end of the upper shield 13b are secured bent-over lugs 15 having slots 16 therein within which slide vertical rods 17 carrying at their lower ends an inverted conical baffle 18. The rods 17 are bent over at the upper ends and are of such a length that the baffle 18 is normally held above the open end of the lower shield 13 and has its widest part level with a series of vent holes 19 formed in the upper shield 13b. The base dimensions of the baffle 18 are preferably substantially equal to or slightly greater than the dimension of the smaller end of shield 13a and of the outlet 11. Secured on the outer surface of shield 13b are a series of downwardly and outwardly directed vent pipes 20 which shroud and terminate at their inner ends in the vent holes 19. The number of vent holes 19 and vent pipes 20 may be varied as desired but conveniently a series of three is provided. The lower ends of the vent pipes are cut at right angles to the cowl axis.

40 The cowl as described above has been found substantially to reduce down-draught and under test to give an upward flow of air through pipe 10 even when located in an air current directed downwardly thereon.

45 The baffle 18 is supported for axial movement in the upper shield 13b to facilitate cleaning of the cowl. This arrangement permits a sweep's brush to enter the upper shield 13b to beyond the level of the vent holes 19.

50 We claim:

1. A cowl comprising a pipe member for mounting the cowl at the end of the flue, chimney or ventilator shaft, said pipe member having a nozzle-like outlet end portion, a plurality of hollow, open-ended, frusto-conical shields carried on the

end of the pipe member above said end portion in vertically superposed relationship, each shield having its narrower end uppermost, each shield except the uppermost shield having its narrower end projecting into and inwardly spaced from the wider end of the shield next above, and the said outlet end portion of the pipe member projecting into and being inwardly spaced from the wider end of the lowermost shield, a plurality of open-ended vent pipes secured externally on the uppermost shield in circumferentially-spaced relationship, each vent pipe extending downwardly and outwardly from the uppermost shield and communicating at its upper end through a vent hole into the interior of the uppermost shield at a level spaced above the narrower end of the shield next below the uppermost shield, and a conical baffle member supported to be wholly within the uppermost shield and above the shield next below and having its apex downwards and its part of maximum diameter level with said vent holes.

2. A cowl as claimed in claim 1, wherein the vent pipes have their lower ends cut at right angles to the cowl axis.

3. A cowl comprising a pipe member for mounting the cowl at the end of a flue, chimney or ventilator shaft, said pipe member having a nozzle-like outlet end portion, a first hollow, open-ended frusto-conical shield carried on the pipe member above said end portion with its narrower end uppermost, the said end portion of the pipe member projecting into and being inwardly spaced from the wider end of said first frusto-conical shield, a second hollow, open-ended frusto-conical shield carried on said first frusto-conical shield vertically above it, said second frusto-conical shield having its narrower end uppermost, and said first frusto-conical shield having its narrower end projecting into and inwardly

spaced from the wider end of the second frusto-conical shield, a plurality of open-ended vent pipes secured externally on said second frusto-conical shield in circumferentially-spaced relation, each vent pipe extending downwardly and outwardly from the second frusto-conical shield and communicating with the interior of the second-frusto-conical shield through vent holes located at a level spaced above the narrower end of the first frusto-conical shield, and a conical baffle member supported to be wholly within the second frusto-conical shield and above the narrower end of the first frusto-conical shield and having its apex downwardly directed and its parts of maximum diameter level with said vent holes.

4. A cowl as claimed in claim 3, wherein the vent pipes have their lower ends cut at right angles to the cowl axis.
